UNITED STATES PATENT OFFICE

149,051

DESIGN FOR A TRANSFER RIBBON UNIT FOR MARKING MACHINES

Herbert E. Edwards, Wellesley Hills, Mass., assignor to T. J. Edwards, Inc., Boston, Mass., a corporation of Massachusetts

Application October 10, 1946, Serial No. 133,862

Term of patent 14 years

(Cl. D64—11)

To all whom it may concern:

Be it known that I, Herbert E. Edwards, a citizen of the United States, residing at Wellesley Hills, in the county of Norfolk and Commonwealth of Massachusetts, have invented a new, original, and ornamental Design for a Transfer Ribbon Unit for Marking Machines, of which the following is a specification, reference being had to the accompanying drawing, forming a part thereof, in which:

Fig. 1 is a plan view of a transfer ribbon unit for marking machines, showing my new design;

Fig. 2 is a view of the unit in elevation as seen from the left-hand side; and

Fig. 3 is a similar view of the unit as seen from the right-hand side.

I claim:

The ornamental design for a transfer ribbon unit for marking machines, substantially as shown.

HERBERT E. EDWARDS.
